FOLDABLE LOCKING TAB FOR
CARTON CONTENT

Arthur J. Weiss, Bergenfield, N.J., assignor to Continental Can Company, Inc., New York, N.Y., a corporation of New York

Filed Feb. 9, 1965, Ser. No. 431,304
8 Claims. (Cl. 206—65)

This invention relates in general to a new locking tab for cartons particularly adapted to receive containers of the type having recessed end panels and surrounding axial projections.

This invention particularly relates to cartons of the wrap-around type which are wrapped around and interlocked with a plurality of like containers arranged in one or more rows. Cartons of the type to which this invention relates are provided with open ends through which it is possible for containers to slide if they are not properly interlocked with the carton. In the past it has been proposed to provide locking tabs which project down into the recessed ends of the containers for locking engagement behind the axial projections of the containers, such projections being chimes or seams when the containers are cans. The locking tabs are struck out of the material of the cartons and are normally reversely folded. However, the locking tabs, after a period of time, assume relaxed positions with the result that they do not fully seat against the end panels and it is possible for the containers, such as cans, to slide past the locking tabs.

It is the purpose of this invention to provide a novel locking tab of the type set forth above wherein full seating of the locking tab within the recessed end of the container is assured at all times. This is accomplished by spacing the body portion of the locking tab from the associated carton panel in a positive manner. The body portion of the locking tab has a terminal flap which is reversely folded with respect to the body portion and which is positioned between the body portion and the carton panel to assure the proper spacing of the remote end of the body portion from the carton panel. That end of the body portion which is directly attached to the carton panel is attached thereto by means of a relatively wide fold line type hinge which, when the body portion is reversely folded relative to the carton panel, provides a relatively wide offset connecting portion which effects the necessary spacing of the body portion from the carton panel.

With the above and other objects in view that will hereinafter appear, the nature of the invention will be more clearly understood by reference to the following detailed description, the appended claims and the several views illustrated in the accompanying drawing.

In the drawing:

FIGURE 1 is a perspective view of a carton formed in accordance with this invention and shows the same in its wrap-around state as it would appear when it is wrapped around two rows of containers.

FIGURE 2 is an enlarged fragmentary longitudinal sectional view taken along the line 2—2 of FIGURE 1 and shows the specific details of the carton and the relationship thereof with respect to containers positioned therein, the containers being shown in phantom lines.

FIGURE 3 is an enlarged fragmentary transverse vertical sectional view taken along the line 3—3 of FIGURE 1 and shows further the specific details of the interlock between the carton and containers disposed in two rows, the containers again being shown in phantom lines.

FIGURE 4 is a fragmentary plan view of the blank from which the carton of FIGURE 1 is formed and shows the specific details of a panel of the blank containing the locking tabs.

2

FIGURE 5 is an enlarged fragmentary bottom perspective view with parts broken away and shown in section of the carton of FIGURE 1 and shows the specific details of one of the locking tabs thereof.

Referring now to the drawings in detail, it will be seen that there is illustrated in FIGURE 1 a carton which is formed in accordance with this invention, the carton being generally referred to by the numeral 10. The carton 10 is specifically formed for receiving six containers arranged in two rows of three containers each. The carton 10 is particularly adapted for receiving cans having recessed end panels and both axial and transverse projecting chimes or seams although the carton 10 may be utilized in the packaging of containers other than cans. Typical cans are shown in FIGURE 2 and are generally referred to by the numeral 11. Each can 11 includes a conventional can body 12 which has an end thereof closed by means of a can end 13. Each can end 13 includes a recessed end panel 14 which is secured to the associated can body 12 by means of a conventional double seam 15 which is broadly considered to be a chime. It is to be noted that the seam or chime 15 projects axially of the end panel 14 and surrounds the same and projects radially outwardly of the can body 12. Inasmuch as the cans 11 in themselves do not form a specific part of this invention from a structure standpoint, no further description will be made here as to the other structural details of the cans 11.

The carton 10 is formed from a one-piece blank which is generally rectangular in outline and which blank is provided with a plurality of transversely extending, interrupted fold lines 16, such as the fold lines 16 illustrated in FIGURE 4. The fold lines 16 divide the blank, which is generally referred to by the numeral 17, into a central panel 18 which becomes the top panel of the carton 10. On each side of the panel 18 is a pair of intermediately located side panels 19 and 20. The side panel 19 has hingedly connected thereto a partial bottom panel 21 while a second partial bottom panel 22 is hingedly connected to the side panel 20. It is to be understood that the opposed edge portions of the bottom panels 21 and 22 are disposed in overlapped relation and are connected together by means of a suitable interlock, such as the interlock 23. Inasmuch as the interlock in itself does not form a part of this invention, it will not be described in detail here.

In order that lower portions of containers, such as cans 11, may be interlocked with the carton 10, the bottom panel 11 is provided with an integral upstanding keel 24. The keel 24 is provided with longitudinally spaced notches 25 arranged in pairs on opposite sides thereof for receiving the chimes or projecting seams 15 of cans or like containers. In addition, the carton 10 is provided along the fold line between the panels 19 and 21 and the fold line between the panels 20 and 22 with generally H-shaped cuts 26 for the purpose of forming openings through which the chime or seams of containers, such as the cans 11, may project to form the desired interlock between outer portions of the carton 11 and the containers at the bottom of the carton 10.

The fold lines 16 are interrupted by generally C-shaped cuts 27 which have extending from the central portions thereof straight cuts 28 extending along the side panels 19 and 20. The cuts 27 and 28 provide outer upper openings through which the upper chimes or seams of the containers may project to provide interlocks between the upper outer portions of the carton 10 and the containers 11.

In order to further stabilize containers within the upper portion of the carton 10, the panel 18 is provided with a plurality of depending tabs or flaps 30 which are spaced longitudinally of the panel 18 along a centrally positioned line. It is to be noted that each tab or flap 30 projects down into the interior of the carton 10 and is clamped

between a pair of adjacent chimes or seams 15, as is clearly shown in FIGURE 3.

In order that the upper ends of the containers 11 may be further interlocked with the carton 10 and movement thereof endwise out of the open ends of the carton 10 thus prevented, the panel 18 is further provided with locking tabs which are generally referred to by the numeral 31. There is one locking tab 31 for each of the terminal containers in each row of containers. Thus, since the carton 10 is particularly adapted for two rows of containers, although there will be six containers within the carton 10, there are only 4 of the locking tabs 31.

Each locking tab 31 is generally triangular in outline, as is best shown in FIGURE 4, and includes a straight side edge 32 and a curved side edge 33. The base of each locking tab 31 is connected to the panel 18 along a fold line 34 which forms a hinge. It is also to be noted that the locking tab 31 has a transversely extending fold line 35, which is preferably disposed parallel to the fold line 34 and which defines a terminal flap 36. That portion of the locking tab 31 disposed between the fold lines 34 and 35 may be considered to be a body portion and is identified by the numeral 37.

At this time it is pointed out that the fold line 35 is of the normal width for fold lines conventionally utilized in conjunction with material of the thickness from which the carton 10 is formed. On the other hand, the fold line 34 is very wide. By making the fold line 34 wide, when the locking tab 31 is struck from the panel 18 and the body portion 37 is folded to a position 180 degrees from its original position, as is shown generally in FIGURES 2, 3 and 5, the material of the wide fold line 34 will define a connecting part 38 which automatically spaces the body portion 37 from the panel 18. Prior to the folding of the body portion 37 completely to its position of FIGURE 3, the locking tab 31 is folded along the fold line 35 so that the terminal flap 36 becomes positioned between the body portion 37 and the panel 18. Thus, the body portion 37 is further spaced from the panel 18 by the terminal flap 36.

It is to be understood that the curved edge 33 of the locking tab 31 is in accordance with the curvature of the projecting part of the container which surrounds the recessed end panel, that is the projecting seam or chime 15. Thus, when the panel 18 is firmly seated on a plurality of the containers 11 in the position shown in FIGURES 2 and 3, that portion of the container 11 engaged by the curved side edge 33 will correspond to the curvature of the projecting seam or chime 15 and form an interlock between the locking tab 31 and the associated container. Inasmuch as the body portion 37 is spaced below the panel 18, it will be readily apparent that a permanent interlock will be retained between the locking tab 31 and the associated container 11.

It is to be noted that the panel 18 is provided with a pair of enlarged openings 40 positioned between the tabs or flaps 30. The openings 40 are finger receiving openings to facilitate the gripping of the carton 10 and the carrying of the package formed therewith.

It is also to be noted that the panel 18 is provided with a depressible flap 41 generally aligned with one of the finger receiving openings 40. The side panel 18 is provided with a plurality of slits 42 extending downwardly in generally diverging relation from the flap 41. The purpose of the flap 41 is to permit the insertion of one's finger behind the upper part of the panel 19 so that an outwardly directed pull may be exerted thereon with the result that the end panel 19 will rupture along the general line of the slits 42.

It will be apparent from the foregoing that the carton 10 is greatly enhanced in its container retaining characteristics by the provision of the specific locking flaps 31. It will also be readily apparent that the locking flaps 31 may be formed from the material of the panel 18 without unduly weakening the panel. In addition, it will

be apparent that the locking flaps 31 are so configurated whereby even though the package of which the carton 10 is a part is stored for a long period of time and relaxation of the material of the carton along the fold lines 5 may occur, the locking tabs 31 will remain fully seated within the recessed ends of the associated containers for prevention of the removal of the containers out through the open ends of the carton.

Although only a preferred embodiment of the invention has been specifically illustrated and described herein, it is to be understood that minor variations may be made in the illustrated carton construction within the spirit and scope of this invention as defined by the appended claims.

15 I claim:

1. In a carton of the wraparound type particularly adapted for use in combination with containers having recessed end panels, a carton panel having a folded locking tab projecting therefrom, said locking tab including a body

20 portion in generally parallel spaced relation to said carton panel, a connecting part between said carton panel and said body portion for spacing said body portion from said carton panel at the connection therewith, and a terminal flap on said body portion disposed between said

25 carton panel and said body portion remote from said connecting part and retaining said body portion in said spaced

relation, said connecting part being a portion of a wide fold line type hinge between said carton panel and said body portion.

30 2. A blank for a carton of the wrap-around type, said carton blank including a panel adapted to engage ends of containers of the recessed end panel type, said panel having a locking tab struck therefrom for folding out of the plane thereof, said locking tab including a body portion

35 connected to said carton panel along a first fold line type hinge, and a terminal flap connected to said body portion along a second fold line type hinge, said first hinge being of a greater transverse dimension than said second hinge to automatically space said body portion from said car-

40 ton panel when said body portion is reversely folded out of said carton panel.

3. The carton blank of claim 2 wherein said first and second fold lines are disposed parallel to said panel sides.

4. The carton blank of claim 2 wherein said first and 45 second fold lines are disposed parallel to said panel sides and said locking tab is triangular in outline.

5. A package comprising a plurality of containers each having at least one end with a recessed end panel and a surrounding axial projection, said containers being ar-

50 ranged in two rows and a carton wrapped around and interlocked with said containers, said carton having a panel opposing said container one ends and engaging said container projections, said carton panel having a locking tab for the terminal containers of each row of containers

55 struck therefrom with the locking tabs for each row of containers facing in the same direction and the locking tabs of the two rows of containers facing away from the others, each locking tab including a body portion in generally parallel spaced relation to said carton panel, a connect-

60 ing part between said carton panel and said body portion for spacing said body portion from said carton panel at the connection therewith, and a terminal flap on said body portion disposed between said carton panel and said body portion remote from said connecting part and

65 retaining said body portion in said spaced relation.

6. The package of claim 5 wherein said connecting

part is a portion of a wide fold line type hinge between

66 said carton panel and said body portion.

7. The package of claim 5 wherein said carton panel

is connected to other carton panels along the sides there-

70 of, and said connecting parts are disposed parallel to said carton panel sides.

8. The package of claim 5 wherein each locking tab is

75 triangular in outline prior to the folding thereof whereby said terminal flap automatically assumes an out of the way

position when folded between said body portion and said carton panel.
